(57) CLAIM

The ornamental design for a housing for a centrifuge, as shown and described.

DESCRIPTION

FIG. 1 is a front view of a housing for a centrifuge;
FIG. 2 is a left side view of FIG. 1;
FIG. 3 is a rear view of FIG. 1;
FIG. 4 is a right side view of FIG. 1;
FIG. 5 is a bottom view of FIG. 1;
FIG. 6 is a top view of FIG. 1; and,
FIG. 7 is a perspective view of FIG. 1.
The broken lines depict portions of the housing for a centrifuge that form no part of the claimed design.
